Des. 238,591
Patented Jan. 27, 1976

238,591

HOODED AQUARIUM UNIT

Robert E. De Shores, 3476 Barbara St., San Pedro, Calif.
90731, and Joseph A. Mendez, 10535 Lindenvale
Road, Whittier, Calif. 90606

Filed June 17, 1974, Ser. No. 479,632

Term of patent 14 years

Int. Cl. D30—02

U.S. Cl. D30—11

FIG. 1.

FIG. 2.

FIG. 3.

FIG. 4.

FIG. 5.

FIG. 1 is a front elevational view of a hooded aquarium unit, showing our new design;

FIG. 2 is a left side elevational view;

FIG. 3 is a cross-sectional view taken along line 3—3 of FIG. 1;

FIG. 4 is a top plan view; and,

FIG. 5 is a rear elevational view.

We claim:

The ornamental design for a hooded aquarium unit, substantially as shown and described.
